RUBBISH COLLECTOR

Karl O. Larson, St. Paul, Minn., assignor to Kol, Inc.,
St. Paul, Minn., a corporation of Minnesota

Filed Sept. 3, 1964, Ser. No. 31,581

Term of patent 14 years

(Cl. D14—3)

FIG. 1

FIG. 2

FIG. 3

FIG. 4

FIG. 6

FIG. 5

FIG. 1 is a view in side elevation of a rubbish collector showing my novel design, the side opposite that shown being a mirror image;

FIG. 2 is a view in front elevation thereof;

FIG. 3 is a view in rear elevation thereof;

FIG. 4 is a view of the top plan thereof;

FIG. 5 is a view of the bottom plan thereof; and

FIG. 6 is a view in perspective.

The characteristic features of the design include the arcuate handle portions at upper corners thereof, with conformably cut away areas of the side panels adjacent thereto, the front panel having an elongated notch therein to define a handle portion, and dual flap elements connected to the side panels, and having edges coinciding with adjacent edges of the cut away areas.

I claim:

The ornamental design for a rubbish collector, as shown and described.
